UNITED STATES PATENT OFFICE

ARTHUR M. CAPPER, OF EMSWORTH, PENNSYLVANIA, ASSIGNOR TO CONTINENTAL ROLL & STEEL FOUNDRY COMPANY, OF EAST CHICAGO, INDIANA, A CORPORATION OF DELAWARE

SLACK ADJUSTER FOR RAILWAY CAR BRAKES

Application filed September 21, 1931. Serial No. 564,050.

This invention relates to railway car brake riggings, and more particularly to slack adjusters therefor.

The common railway brake rigging comprises brake actuating levers arranged one at each side of a car truck bolster and joined at their lower ends by a connecting rod. One of these, the live lever, is pivotally connected to a brake actuating mechanism, and the other, the dead lever, is pivotally and adjustably connected at its upper end to the truck bolster or to the bottom of the car. To take up the lost motion developed in the brake rigging by wear on the moving parts and on the brake shoes, the upper or fulcrum end of the dead lever is moved away from the bolster the desired distance, and there secured. There are various means for adjustably connecting the dead lever to the truck bolster or car, but those which are most accessible to adjustment comprise several parts that make the structure complex and expensive, while those which require but few parts can be adjusted only with difficulty by crawling beneath the car truck and working in cramped quarters.

It is among the objects of this invention to provide a slack adjuster for railway car brakes which requires only two parts, is readily accessible to adjustment without going beneath the car, is simple and inexpensive, and insures proper brake clearance after all slack has been taken up.

The invention is illustrated in the accompanying drawing, of which Fig. 1 is a longitudinal section of a car truck supporting one end of a railway car partly shown; Fig. 2 a sectional view of a bracket, taken on the line 11—11 of Fig. 1; Fig. 3 a sectional view taken on the line III—III of Fig. 2; and Fig. 4 a sectional view of the center sill of the railway car, taken on the line IV—IV of Fig. 1, showing a manner of mounting the bracket on the sill.

In accordance with the invention a tension member is attached to the dead lever for shifting the fulcrum thereof to take up slack, the opposite end of the member being adjustably secured in a bracket mounted on the center sill of the car, said bracket being adapted to in-

sure proper brake clearance after said slack has been taken up as far as possible.

Referring to the drawing, a car truck having wheels 1 and supporting one end of a railway car 2 on bolster 3 is equipped with the usual brake rigging. Brake shoes 4, adapted to engage the wheels, are mounted on the ends of brake beams 5. Secured to the middle of each beam is a horizontally disposed strut 6 in one of which live lever 7 is pivotally mounted at one side of the bolster, dead lever 8 being so mounted in the other. Lever 7 is connected at its upper end by rod 9 to a suitable source of brake actuating power, not shown, while the upper end of the dead lever is held in adjustable position to form a fulcrum point. The lower ends of the levers are pivotally connected by a rod 10 in the usual manner.

The means for securing the dead lever 8 in position comprises a chain 11 fastened at one end to the upper end of this lever, and a bracket 12 mounted on center sill 13 near the end of the car. As shown in Fig. 4 of the drawing, base 16 of the bracket is secured to the bottom and at one side of the sill in any suitable manner, such as by bolts extending through apertures in the bracket base and flange 17 of the center sill. To make it possible to take up lost motion in the rigging caused by wear of the parts, and particularly by wear on the brake shoes, bracket 12 is bifurcated, forming jaws 14 with a slot 15 between them extending from the outer end of the bracket to its base. This slot is just wide enough to accommodate a link of chain 11 lying in a plane parallel to the slot, the jaws holding the chain against longitudinal movement by engaging an adjacent link lying in a plane at right angles to that of the one disposed in the slot. As shown in Fig. 2, the faces of the jaws are curved inwardly to conform generally to the contour of the links so that the jaws will have sufficient cross sectional area to withstand the strain exerted upon them by the chain.

An important feature of the invention is the provision of means for preventing the chain from being taken up so far as to cause the brakes to drag. This is accomplished, as shown in the drawing, by having jaws 14 ex-

- tend outwardly and obliquely away from the dead lever at such an angle that the distance between a line dropped from the forward edge of the outer end of slot 15 and the forward edge of the inner end of the slot is such that proper brake clearance is provided when the chain is in locked position in the bracket after having been pulled far enough to take up all slack and then slipped into the slot.
- 10 Thus, when it is desired to take up slack in the rigging, chain 11 is slipped out of slot 15 and is pulled until the brake shoes engage the wheels without danger of causing the brakes to drag, for when the chain is slipped back 15 into the slot it is locked at the inner end thereof which is closer to the dead lever than the outer end of the slot, thereby restoring sufficient slack to the rigging to provide the proper brake clearance.
- 20 Due to the position of bracket 12 on the sill near the end of the car, slack can be adjusted without crawling under the car, and with only the effort required to pull the chain. The apparatus is simple and inexpensive because it comprises only the chain and the anchoring member, and further, danger of taking up the slack too far is eliminated.

According to the provisions of the patent statutes, I have explained the principle and 30 operation of my invention and have described what I now consider to be its best embodiment. However, I desire to have it understood that within the scope of the appended claims, the invention may be practiced otherwise than as specifically described.

I claim:

1. In a slack adjuster for railway car brakes, the combination with a car having a center sill and a brake rigging including a 40 dead lever, of a tension member attached to said dead lever for shifting the fulcrum thereof, and holding it in different positions, and a bifurcated bracket mounted on said center sill and having jaws adapted to secure 45 said tension member between them to permit slack in the brake rigging to be taken up, said jaws projecting outwardly and obliquely away from said dead lever to such extent that when the tension member is pulled free from 50 said jaws and sufficiently to apply the brakes and is then engaged by the jaws it is locked thereby at proper brake-clearance position.
2. In a slack adjuster for railway car brakes, the combination with a car having a 55 center sill and a brake rigging including a dead lever, of a chain attached to the upper end of said dead lever for shifting the fulcrum thereof and holding it in different positions, and a bifurcated bracket mounted on 60 said sill and having jaws for engaging and securing said chain between them to permit slack in the brake rigging to be taken up, said jaws projecting outwardly and obliquely away from said dead lever to such extent that 65 when the chain is pulled free from said jaws

and sufficiently to apply the brakes and is then engaged by the jaws it is locked thereby at proper brake-clearance position.

In testimony whereof, I sign my name.

ARTHUR M. CAPPER.
